UNITED STATES PATENT OFFICE.

FRANK BUSALD, OF COSHOCTON, OHIO.

DOUBLE-FACER.

956,794.

Specification of Letters Patent. Patented May 3, 1910.

Application filed July 26, 1909. Serial No. 509,561.

To all whom it may concern:

Be it known that I, FRANK BUSALD, citizen of the United States, residing at Coshocton, in the county of Coshocton and State of Ohio, have invented certain new and useful Improvements in Double-Facers, of which the following is a specification.

This invention relates to machines for applying facing to corrugated paper and more particularly to a machine for applying a second facing sheet to single faced corrugated paper.

The object of the invention is to provide a machine of simple and durable construction, by means of which one or more facing sheets may be applied to a corrugated strip and the composite sheet cut into predetermined lengths at one operation of the machine.

20 A further object is to provide a facing machine, the construction of which is such that both sides of the corrugated strip are heated and held in contact with the facing strip during the passage of said strips through the machine thus preventing cupping of the resultant product and producing a smooth straight composite sheet.

25 A further object is to provide a cutting device including an oscillating frame having a blade mounted for reciprocation thereon and operatively connected with the strip feeding mechanism, said cutting device being actuated intermittently to cut the double faced corrugated strip into predetermined lengths.

30 A still further object of the invention is generally to improve this class of devices so as to increase their utility, durability and efficiency.

35 40 Further objects and advantages will appear in the following description, it being understood that various changes in form, proportions and minor details of construction may be resorted to within the scope of the appended claims.

45 For a full understanding of the invention and the merits thereof and also to acquire a knowledge of the details of construction and the means for effecting the result, reference 50 is to be had to the following description and accompanying drawings, in which:

55 Figure 1 is a side elevation of a double facing machine constructed in accordance with my invention; Fig. 2 is a longitudinal sectional view of the same; Fig. 3 is a plan view; Fig. 4 is a transverse sectional view

taken on the line 4—4 of Fig. 3; Fig. 5 is a perspective view of the cutting mechanism and the adjacent portion of the supporting frame.

60 Corresponding and like parts are referred to in the following description and indicated in all the views of the drawings by the same reference characters.

The machine forming the subject matter 65 of the present invention is principally designed for applying a second facing to a corrugated strip after the latter has been passed through a corrugating machine and the first facing applied thereto.

70 The machine comprises a supporting frame including spaced side walls 5 having depending feet 6 bolted or otherwise rigidly secured thereto and upon which is mounted a casing or housing 7.

75 Journaled in the side walls 5 of the supporting frame, are a series of spaced horizontally aligned feed rollers or cylinders 8, the latter being hollow and preferably extended the entire width of the casing 7, as shown.

80 Disposed beneath the feed rollers 8 and preferably arranged in vertical alinement therewith, are similar feed rollers 9, which in conjunction with the rollers 8 serve to press 85 the facing strip in contact with the corrugated strip as said strips are fed through the machine.

85 The upper and lower feed rollers 8 and 9 are hollow to provide steam chambers 10, in order that the rollers may be kept at the proper temperature to insure drying of the paste or other adhesive material applied to the corrugated strip.

90 Each feed roller is provided with oppositely disposed spindles 11 which project through bearings 12 in the side walls 5 of the supporting frame, there being suitable pockets 13 formed in the side walls 5 beneath the projecting end of each spindle 11. 100 The upper ends of the pockets 13 are open, while the lower ends thereof are provided with threaded apertures for the reception of set screws 14 by means of which the distance between the adjacent rollers may be regulated so as to accommodate strips of paper of different thicknesses.

105 The spindles 11 on one side of the machine are provided with longitudinal openings which communicate with the steam chambers 110 10 and in which are seated the sleeves or bushings 15 of suitable sprocket wheels 16.

The bushings 15 are secured to the adjacent spindles 11 by screws or similar fastening devices 17 so that the sprocket wheels will be rotated with the drums or rollers.

5 Steam is supplied to the compartments 10 of the several drums or rollers 8 and 9 through pipes or conductors 18, two of which are preferably extended through each bushing 15. One of the pipes 18 of each drum or 10 roller is connected with a main supply pipe 19, while the other pipe 18 is connected with an exhaust pipe 20 so that the steam entering through the pipe 19 is free to circulate within the compartments 10 and exhaust 15 into the pipe 20, there being a suitable steam trap 21 operatively connected with the pipes 19 and 20 at the forward end of the machine, as shown.

Disposed within the casing or housing 7 20 and interposed between the feed rollers or drums, are steam chests, the abutting faces of the steam chests being flat and unobstructed and spaced apart to permit the passage of the corrugated strip and facing 25 strip through the machine.

The steam chests 22 are connected by branch pipes 23 so as to allow a continuous circulation through the several steam chests for the purpose of maintaining the latter at 30 the proper temperature, steam being admitted to the upper and lower steam chests at one end of the machine through a pipe or conductor 24 and being exhausted from the steam chest at the other end of the machine 35 through a similar pipe or conductor 25 communicating with the pipe 23.

The upper series of rollers or drums are driven by a sprocket chain 27 engaging the sprocket wheels 16, while the lower set or 40 series of rollers 9, are driven by frictional contact with the paper strip as the latter passes through the machine.

One of the drums or rollers 8 of the upper series is provided with a relatively large 45 sprocket wheel 28, which latter is connected through the medium of a sprocket chain 29 with a motor engine or other source of power, thereby to rotate the several feed rollers or drums.

50 A sprocket chain 30 engages the teeth of the sprocket wheels 16 on the lower set or series 9 in order that said rollers may rotate in unison.

Extending laterally and upwardly from 55 one end of the machine, are spaced brackets 31 having terminal bearings 32, in which is journaled a spool or spindle 33 carrying a roll of facing paper 34, which latter is fed through the machine together with the corrugated strip 35 and secured to the latter in 60 order to produce the composite sheet, indicated at 36.

Disposed beneath the spool carrying bracket 31, is a second bracket 37, to which 65 is secured in any suitable manner, a paste

cup or tank 38. Mounted for rotation within the paste cup or tank 38 and journaled in suitable bearings 39 in the bracket 37, is a roller 40 which applies the paste or other adhesive material in the cup to the adjacent 70 face of the corrugated strip 35 as the latter is fed through the machine. Journaled in bearings in the lower portion of the bracket 37, are a plurality of feed rollers 41, each having one end thereof extended to form a 75 spindle 42, to which is secured a sprocket wheel 43. A sprocket chain 44 engages the sprocket wheel 43 of the feed rollers and also passes around a sprocket wheel 45 on the spindle of the paste applying roller 40, 80 the latter being provided with a similar sprocket wheel 46 which engages the sprocket chain 27 so that motion may be transmitted through the medium of the sprocket chain 27 to the paste applying roller 40 and thence 85 through the medium of the chain 44 to the feed rollers 41, as best shown in Fig. 1 of the drawings.

The supporting feet or legs at the front of the machine are extended laterally and provided with horizontally aligned bearings 47, in which is mounted for rotation a transverse shaft 48 having spaced eccentrics 49 secured to the opposite ends thereof and which co-act with suitable eccentric straps 50. 90

Mounted for oscillation on the shaft 48, is a frame, the side bars 51 of which are pivotally mounted at their lower ends on the shaft 48, while their upper ends are formed with vertically disposed slots 52, in which is 100 mounted a reciprocating cutting blade or knife 53. The opposite ends of the cutting blade 53 are reduced and projected through the slots 52 for connection with vertically disposed rods 54, said rods forming a connection between the eccentric straps 50 and the opposite ends of the cutting blades 53, as best shown in Fig. 5 of the drawings. Connecting the bars 51 of the oscillating frame beneath the slots 52, is a bed plate 55 which 105 co-acts with the knife 53 to cut or sever the composite strip into predetermined lengths.

Motion is imparted to the oscillating frame 51 by means of an arm 56, one end of which is secured to the adjacent side bar of 110 the frame 51, while the other end thereof extends above the sprocket chain 31 and is provided with a terminal lip or finger 57, which latter extends into the path of movement of an actuating finger or lug 58 carried by the sprocket chain 30. Thus it will be seen that as the sprocket chain 30 rotates, the pin or lug 58 will intermittently engage the finger 57 of the arm 56 and force the oscillating frame 51 laterally to the dotted 115 line position shown in Fig. 1 of the drawings, said oscillating frame being returned to normal or vertical position by means of a coil spring 59 operatively connected with the frame 51 and supporting frame 5. 120

5 loosely mounted for rotation on one end of the transverse shaft 48, is a wheel or pulley 60, over which travels a belt 61 leading to a motor or other suitable source of power for actuating the cutting blade 53.

10 The inner face of the wheel or pulley 60 is provided with a clutch member 62, there being a similar clutch member 63 keyed to the shaft 48 and adapted to engage the mating clutch member 62 for transmitting motion from the pulley 60 to the shaft 48.

Pivotaly mounted at 64 on one of the side members of the oscillating frame 51, is a lever 65, one end of which is bifurcated 15 for engagement with the movable clutch member 63 so that when the lever 65 is tilted, the clutch members 62 and 63 will be moved into and out of engagement with each other.

20 The free end of the operating lever 65 travels in the path of an inclined bar or cam 66 carried by the supporting frame 5 so that when the oscillating frame 51 is swung laterally away from the machine, the lever 65, by engagement with the cam 66, will actuate the clutch members to key the pulley 60 on the shaft 48, thereby to actuate the knife and cut or sever a predetermined length of the composite strip.

25 In order to disengage the clutch members 62 and 63 after each downward movement of the knife 53, there is provided a spring 67, one end of which is secured to the lever 65, while the opposite end thereof is secured 30 to one of the side members of the frame 51. Thus it will be seen that when the lug 58 engages the lip on the arm 56, the oscillating frame 51 will be swung laterally, thereby causing the cam 66 to trip the lever 65 and 35 throw the clutch members 62 and 63 into engagement with each other and rotate the shaft 48. As the shaft 48 rotates, the eccentrics 49 will actuate the rods 54 to lower the cutting blade 53 in the direction of the

40 plate 55 and cut or sever the composite strip. After the lug 58 is disengaged from the arm 56, the spring 59 will automatically return the frame 51 to normal or vertical position, and in doing so cause the cam 66 to actuate 45 the lever 65 and disengage the clutch members 63 so that the cutting mechanism will remain dormant until the lug 58 again engages the finger on the arm 56, in the manner before stated.

50 The casing or housing 7 is preferably lined with a jacket of asbestos 68, while the top of the casing is provided with a pivoted cover 69 so that access may be readily had to the interior of the casing to effect any 55 necessary repairs to the feed rollers and steam chests.

In operation, the corrugated strip having a single facing applied thereto, is fed through the corrugating machine or from 55 a suitable drum or reel, to the feed rollers

41 and thence over the roller 40 and idle roller 70, the roller 40 applying the paste or other adhesive material to the corrugated side of the strip during its passage to the feed rollers 8 and 9. As the corrugated strip 35 having single facing applied thereto, is fed between the upper and lower series of feed rollers 8 and 9, the facing strip 34, by frictional engagement with the strip 35, will be withdrawn from the spool 33 and 70 forced in contact with the adhesive material on the corrugated strip 35, the steam in the feed rollers 8 and 9 and steam chests 22, serving to dry the adhesive material as said strips are pressed together so as to form a 75 composite strip comprising a corrugated body portion having its opposite sides covered with a facing of paper. As the composite strip is fed through the front of the machine, the arm 56, by engagement with 80 the lug 58, will intermittently actuate the cutting device to cut or sever said composite strip into predetermined lengths, which strips may be piled on a table or other support 71 designed to receive the same. 85

90 By changing the position of the lug 58 on the sprocket chain 30, or by lengthening or shortening the arm 56, the lengths of the strips of composite paper may be varied at will.

95 If desired, one of the sprocket chains 30 may be used on each side of the machine, and in some cases, the clutch members 62 and 63 may be actuated manually instead of automatically. 100

105 It will here be noted that the outer or free end of the cam 66 terminates in an angularly disposed lip 72 which forms a stop and serves to limit the outward swinging movement of the oscillating frame 51, 110 while the spring 59 serves to limit the inward movement thereof.

Having thus described the invention, what is claimed as new is:

1. In a machine of the class described, 110 means for feeding a strip of single faced corrugated paper and a strip of facing paper through the machine, means for applying adhesive material to one side of the corrugated paper before its passage through the 115 machine, means for heating said strips of paper and pressing them together, a frame mounted for oscillation at one end of the machine, a cutting blade slidably mounted on the oscillating frame, and means operatively connected with the oscillating frame and actuated by the feeding mechanism for reciprocating the cutting blade intermittently, thereby to cut the composite strip into predetermined lengths. 120

125 2. In a machine of the class described, a supporting frame, upper and lower sets of hollow feed rollers journaled in the supporting frame and spaced apart to produce an intermediate passage for the reception of a 130

- strip of single faced corrugated paper and a strip of facing paper, means for feeding said strips through said passage to produce a composite strip, and a cutting device mounted for oscillation on one end of the frame and operable by the paper feeding mechanism for intermittently cutting said composite sheet into predetermined lengths.
3. In a machine of the class described, a supporting frame, a plurality of sets of hollow feed rollers journaled in the frame and spaced apart to produce an intermediate passage, means for heating said rollers, independent sprocket chains connecting each set of rollers, a lug carried by one of the sprocket chains, means for feeding a strip of single faced corrugated paper and a strip of facing paper through the passage between the feed rollers, an oscillating frame disposed at one end of the machine and provided with a cutting blade, and an arm carried by the oscillating frame and extended into the path of movement of the lug on said sprocket chain for actuating the cutting blade to sever the material into predetermined lengths.
4. In a machine of the class described, a supporting frame, upper and lower sets of feed rollers in the frame and spaced apart to produce an intermediate passage, steam chests disposed between the feed rollers of each set, means for heating the feed rollers, means for feeding a strip of single faced corrugated paper and a strip of facing paper through the passage to produce a composite strip, a frame mounted for oscillation at one end of the machine and provided with a table, a cutting blade mounted for reciprocation on the oscillating frame, means for rotating the upper and lower sets of feed rollers, an arm projecting from the oscillating frame, and a lug arranged to travel with the lower set of feed rollers and adapted to engage the arm for actuating the cutting blade.
5. In a machine of the class described, a supporting frame, means for feeding a strip of single faced corrugated paper and a strip of facing paper through the machine to form a composite strip, a shaft mounted for rotation at one end of the machine and provided with an eccentric, a frame mounted for oscillation on the shaft, a cutting blade mounted for reciprocation in the oscillating frame, a rod forming a connection between the cutting blade and eccentric, and means forming a connection between the oscillating frame and the paper feeding means for actuating the cutting blade to cut or sever the composite strip into predetermined lengths.
6. In a machine of the class described, a supporting frame, means for feeding a strip of single faced corrugated paper and a strip of facing paper through the machine to form a composite strip, a shaft journaled on one end of the frame, a frame mounted for oscillation on said shaft, a cutter carried by and slidably mounted on the oscillating frame, means connected with the oscillating frame and operable by engagement with the paper feeding mechanism for oscillating the frame and simultaneously actuating the cutting blade, and means for automatically returning the oscillating frame to normal position after each stroke of the cutting blade.
7. In a machine of the class described, a supporting frame means for feeding a strip of single faced corrugated paper and a strip of facing paper through the machine to form a composite strip, a frame mounted for oscillation at one end of the machine, a cutting blade carried by and slidably mounted on the oscillating frame, means actuated by the paper feeding mechanism for oscillating the frame and actuating the cutter at one stage or operation of the machine, and means for automatically returning the oscillating frame to normal position and elevating the cutting blade at another stage or operation of the machine.
8. In a machine of the class described, a supporting frame, means for feeding a strip of single faced corrugated paper and a strip of facing paper through the machine to produce a composite strip, a shaft journaled on one end of the supporting frame, an oscillating frame mounted on the shaft, a cutting blade mounted for reciprocation in the oscillating frame, a power pulley loosely mounted on the shaft and provided with a clutch member, a mating clutch member keyed to the shaft, spaced eccentrics carried by the shaft and operatively connected with the cutting blade for actuating the latter, a lever pivotally mounted on the oscillating frame for moving the clutch members into and out of engagement with each other, and means operable by the paper feeding mechanism for oscillating the frame and simultaneously throwing the clutch members into engagement with each other, thereby to operate the cutting blade.
9. In a machine of the class described, a supporting frame, means for feeding a strip of single faced corrugated paper and a strip of facing paper through the machine, a shaft journaled on the supporting frame, a power pulley loosely mounted for rotation on one end of the shaft and provided with a clutch member, an oscillating frame carried by said shaft, a cutting blade mounted for reciprocation in the oscillating frame, eccentrics carried by the shaft and operatively connected with the cutting blade, a mating clutch member, a lever pivotally mounted on the oscillating frame for moving the clutch members into and out of engagement with each other, means operable by the paper feeding mechanism for tilting

the oscillating frame, and a cam carried by the supporting frame and adapted to actuate the lever to throw the clutch members into engagement with each other when the 5 oscillating frame is moved in one direction and to disengage said clutch members when the oscillating frame is moved in the other direction.

10. In a machine of the class described, a 10 supporting frame, means for feeding a strip of single faced corrugated paper and a strip of facing paper through the machine, a power shaft journaled on one end of the machine and provided with mating clutch 15 members, an oscillating cutting device carried by the shaft, means actuated by the paper feeding mechanism for oscillating the frame, means for throwing the clutch members into engagement with each other when 20 the oscillating frame is tilted in one direction, and means for disengaging the clutch members when the oscillating frame is moved in the other direction.

11. In a machine of the class described including a supporting frame, means for feeding a strip of single faced corrugated paper and a strip of facing paper through the machine, an oscillating frame pivotally mounted for tilting movement on one end of 25 the supporting frame, a cutting blade carried by and slidably mounted on the oscillating frame, means actuated by the paper feeding mechanism for tilting the oscillating frame, and means for actuating the cutter when the oscillating frame is moved in 30 one direction and for returning the cutting blade to normal position when the oscillating frame is moved in the other direction.

12. In a machine of the class described, a 40 supporting frame, means for feeding a strip of single faced corrugated paper and a strip of facing paper through the machine, a power shaft journaled on one end of the supporting frame and having a wheel loosely 45 mounted for rotation thereon and provided with a clutch member, a mating clutch mem-

ber keyed to the shaft, an oscillating frame mounted for tilting movement on said shaft, a cutting blade mounted for reciprocation on the oscillating frame, a trip arm carried by the oscillating frame and actuated by the paper feeding mechanism for tilting the oscillating frame, and means for throwing the clutch members into engagement with each other to actuate the cutting blade when the 55 oscillating frame is moved in one direction and to return the blade to normal position when the frame is moved in another direction.

13. In a machine of the class described, a 60 supporting frame, means for feeding a strip of single faced corrugated paper and a strip of facing paper through the machine, a power shaft mounted for rotation on one end of the supporting frame, a wheel loosely 65 mounted on the shaft and provided with a clutch member, a mating clutch member keyed to the shaft, an oscillating frame pivotally mounted for tilting movement on said shaft and provided with a table, a cutting 70 blade co-acting with the table, a lever pivotally mounted on the oscillating frame and operatively connected with the movable clutch member, a trip arm carried by the oscillating frame and actuated by the paper 75 feeding mechanism for intermittently tilting the oscillating frame, and a cam carried by the supporting frame and adapted to engage the operating lever for throwing the clutch members into engagement with each 80 other and actuating the cutting blade when the oscillating frame is tilted in one direction and to release the clutch members and return the cutting blade to normal position when the oscillating frame is moved in an 85 other direction.

In testimony whereof I affix my signature in presence of two witnesses.

FRANK BUSALD. [L. S.]
